DISSECTING TABLE OR THE LIKE

Vernon R. Berlin, Greece, N.Y., assignor to Holderle
Brothers, Inc., Rochester, N.Y., a corporation of New
York

Filed June 22, 1964, Ser. No. 80,495

Term of patent 14 years

(Cl. D83—1)

FIG. 2

FIG. 3

FIG. 1 is a perspective view of a dissecting table or the like, with the hinged cover sections in closed position, showing my new design;

FIG. 2 is a similar perspective view of the same, with the hinged cover sections swung to open position; and

FIG. 3 is a vertical section taken transversely through the table approximately at the mid-point of its length, with the cover sections closed.

The sides not shown in the perspective views are similar to the respective sides shown.

I claim:

The ornamental design for a dissecting table or the like, substantially as shown and described.
